UNITED STATES PATENT OFFICE

131,212

DESIGN FOR A FRONT FENDER FOR AN AUTOMOBILE

Ronald J. Waterbury, Birmingham, Mich., assignor to General Motors Corporation, Detroit, Mich., a corporation of Delaware

Application February 27, 1941, Serial No. 99,260

Term of patent 7 years

To all whom it may concern:

Be it known that I, Ronald J. Waterbury, a citizen of the United States and a resident of Birmingham, county of Oakland, and State of Michigan, have invented a new, original, and ornamental Design for a Front Fender for an Automobile, of which the following is a specification, reference being made to the accompanying drawing, forming a part thereof.

Figure 1 is a plan view of a front fender for an automobile showing my new design.

Figure 2 is a side elevational view of the fender.

Figure 3 is a front elevational view of the fender.

I claim:

The ornamental design for a front fender for an automobile, as shown.

RONALD J. WATERBURY.
